UNITED STATES PATENT OFFICE.

BENJAMIN F. FORSYTH, OF CHICAGO, ILLINOIS.

ADJUSTABLE SEAT.

Application filed August 23, 1926. Serial No. 130,827.

My invention relates to improvements in adjustable seats and has for its object the provision of an improved construction of this character so constructed and arranged that 5 the seat member may be readily adjusted and securely locked in adjusted positions.

Other objects will appear hereinafter.

The invention consists in the combinations and arrangements of parts hereinafter described and claimed.

The invention will be best understood by reference to the accompanying drawings, forming a part of this specification and in which,

15 Fig. 1 is a side view of a seat embodying the invention;

Fig. 2 an enlarged sectional view illustrating a clamping member employed in the construction;

20 Fig. 3 an enlarged section taken substantially on line 3—3 of Fig. 1; and

Fig. 4 a section taken on line 4—4 of Fig. 1.

The preferred form of construction, as illustrated in the drawings, comprises a tubular post 5 mounted upon a suitable base or foot member 6 as shown. The post 5 is provided with a guide slot 7 in its front face, and the sleeve 8 is slidably mounted on said post as shown. The sleeve 8 is provided in its 25 front wall with a recess 9 exposing a portion of the front wall of the post 5 including the slot 7, and a back member 10 is secured to the upper portion of said sleeve. A clamping plate 11 is fitted into the recess 9 and rests

30 against the front face of the post 5, a corresponding clamping block 12 being fitted to the inner wall of the post 5 as shown. The clamping plate 11 and the clamping block 12 are centrally slotted to permit of the free 35 passage of a clamping arm 13 as shown. The clamping arm 13 carries a cross pin 14 in its lower portion resting against the outer face of the plate 11, and a cross pin 15 is seated in a notch 16 in the upper portion of the 40

45 clamping arm 13 within the post 5, said cross pin 15 resting adjacent the inner face of the clamping block 12. The arrangement is such that downward swinging of the clamping arm 13 forces the clamping plate 11 inwardly, and the clamping block 12 outwardly, thus 50 securely clamping the wall of the post 5 between them.

A seat member 17 is mounted on the outer 55 end of the clamping arm 13 as shown, and said clamping arm is provided with a depending guide arm 18 passing through a suitable open-

ing in the sleeve 8 and operating freely in the slot 7, said guide arm thus maintaining the parts in proper relation. Notches 19 are provided in the recess 9 and corresponding transverse openings 20 are provided in the side walls of the post 5, by means of which the pin 15 may be readily removed and inserted for disassembling or assembling the parts.

By this arrangement it will be observed that 65 the seat 17 may be readily adjusted vertically upon the post 5, the weight of the seat itself serving to cause sufficient clamping action to hold the seat in adjusted positions. When the weight of a person is applied to the seat 70 member, the clamping plate 11 and the clamping block 12 are forced into powerful clamping engagement with the front wall of the post 5, thereby automatically locking the seat by the application of the weight thereon. The 75 specific form and arrangement of parts is a simple and effective one for the purpose.

While I have illustrated and described the preferred form of construction for carrying my invention into effect, this is capable of 80 variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. An adjustable seat comprising a tubular post having a slot in one side; a sleeve slideable on said post and having a recess in one side exposing said slot; a back member carried by said sleeve; a seat member provided with a clamping arm extending through said recess and said slot; a clamping plate fitting in said recess and resting against the outer side of said post; a cross pin in the lower portion of said clamping arm resting against the outer face of said clamping plate; a clamping block arranged on the inner side of said post, said clamping plate and block being slotted for the free passage of said clamping arm; and a cross pin mounted in the upper portion of said clamping arm and resting against the inner side of said clamping block, substantially as described.

2. An adjustable seat comprising a tubular post having a slot in one side; a sleeve slideable on said post and having a recess in one side exposing said slot; a back member car-

ried by said sleeve; a seat member provided with a clamping arm extending through said recess and said slot; a clamping plate fitting in said recess and resting against the outer side of said post; a cross pin in the lower portion of said clamping arm resting against the outer face of said clamping plate; a clamping block arranged on the inner side of said post, said clamping plate and block being slotted for the free passage of said clamping arm; a cross pin mounted in the upper por-

tion of said clamping arm and resting against the inner side of said clamping block; and a guide arm depending from said clamping arm and operating in the slot in said post, said sleeve being provided with an opening for the passage of said guide arm, substantially as described.

In testimony whereof I have signed my name to this specification.

BENJAMIN F. FORSYTH.
